UNITED STATES PATENT OFFICE

155,357

DESIGN FOR AN ELECTRONIC TUBE RADIATOR CAP

Charles O'Rourke, deceased, late of Brooklyn,
N. Y., by Bessie O'Rourke, administratrix,
Brooklyn, N. Y., assignor to Sylvania Electric
Products, Inc., a corporation of Massachusetts

Application March 2, 1948, Serial No. 144,864

Term of patent 14 years

(Cl. D26—1)

To all whom it may concern:

Be it known that Charles O'Rourke, deceased, while a citizen of the United States of America, residing at 611 Bainbridge Street, Brooklyn, in the county of Kings, in the State of New York, invented a new, original, and ornamental Design for an Electronic Tube Radiator Cap, of which the following is a specification, reference being had to the accompanying drawing, forming a part thereof, in which:

Fig. 1 is a top plan view of the radiator cap mounted on an electronic tube;

Fig. 2 is a front elevation of the radiator cap as positioned on an electronic tube;

Fig. 3 is an enlarged top plan view of the radiator cap and

Fig. 4 is an enlarged front elevation of the radiator cap as shown in Fig. 2 embodying the new design.

The dotted lines are shown for illustrative purposes only.

What is claimed is:

The ornamental design for an electronic tube radiator cap, as shown and described.

BESSIE O'ROURKE,
Administratrix of the Estate of Charles O'Rourke,
Deceased.
